ATTORNEY.

UNITED STATES PATENT OFFICE.

WILLIAM G. CHAPIN, OF BROOKLYN, NEW YORK.

CORRUGATED BOX-BOARD.

No. 918,964.

Specification of Letters Patent. Patented April 20, 1909.

Application filed March 11, 1908. Serial No. 420,366.

To all whom it may concern:

Be it known that I, WILLIAM G. CHAPIN, a citizen of the United States, residing at Brooklyn, in the county of Kings and State 5 of New York, have invented certain new and useful Improvements in Corrugated Box-Boards, of which the following is a specification.

The immediate object of this invention is 10 to provide effective, and reasonably cheap, means for stiffening so-called "corrugated" boards, of the class now commonly used in the manufacture of boxes, cartons, cloth-boards, photo-mailing wrappers, and analogous articles; my present aim being to produce an exceptionally stiff and strong package 15 of light weight.

My said improvement is clearly illustrated in the annexed drawings, Figure 1 being a 20 plan view of a box or cover blank reinforced according to my present plan, and Fig. 2 is a sectional view of the same taken on line 2—2. Fig. 3 is a perspective view of said box or cover as it appears when completed. 25 Fig. 4 is a perspective view, partly in section, of a portion of a reinforced box blank. Fig. 5 shows a section of corrugated board having a stiffening strip that is somewhat narrower than the depth of the box or cover for a purpose hereinafter explained, and in Fig. 6 I 30 have illustrated, in section, a similar piece of board having the stiffening strip secured to the edge of said board by overlapping strips of paper or cloth.

35 The material which I preferably make use of is "double lined" corrugated board, substantially of the form illustrated in the accompanying drawings, and indicated therein by the reference numeral 10. This provides 40 a smooth-faced board having a light, but very stiff, skeleton that will resist great crushing strain and, in order to further strengthen such boards, I reinforce one or more of the edge portions thereof as I will 45 now explain.

Assuming that it is desired to reinforce a box or cover, a blank of suitable size is first cut from double-faced corrugated board; The skeleton of corrugated material is then 50 preferably cut away between the opposing cover sheets, to a depth equal, or about equal to the width of the reinforcing strip 11 which latter is then inserted in the saw kerf (completely filling said kerf) and is secured there- 55 in by glue, wire staples or other inexpensive means. In the case of boxes and covers, or

of flat boards for mailing photos, calendars and the like articles, I preferably reinforce and stiffen all of the four edges of the board; the box or cover blanks being then properly 60 scored, cornered, broken up, and wired, or otherwise stayed, at the corners, as seen at 12 in Fig. 3 of the drawings. If desired, the reinforced edges may be completely hidden from sight by cover papers. 65

In the slight modification of my invention illustrated in Fig. 5 of the drawings the reinforcing strip 11 is of less width than the depth of the box or cover, as the case may be and is somewhat thinner than the corrugated skeleton, so that, when the cover papers are secured to said strip, the edge portion of the reinforced sheet is thinner than the body portion, this construction being desirable in covers or boxes that are to be 75 nested for shipment.

In the modification of Fig. 6 the stiffening strip abuts the edge of the double-faced corrugated board and is secured to said board, so that it forms an extension thereof, by 80 special binding strips 12 which, if so desired, may be of cloth, thus adding to the strength and stiffness of the edge portion of the board. This construction may also be utilized to provide an edge portion that is relatively thinner than the body of the board. The stiffening strips 11 may be of wood, heavy cardboard or other cheap material that is relatively stiffer than the corrugated board. Said strips add but little to the cost yet they 85 effectually prevent the cutting in of strings and also render such reinforced boards capable of withstanding great crushing and breaking strains and, in most instances, obviate the necessity of crating boxes and cartons 90 embodying my described improvement. 95

Having thus described my invention I claim:

1. In combination with a double-faced corrugated board having the corrugated skeleton cut away substantially as described, a stiffening strip of relatively stiffer material inserted between the opposing facing sheets and occupying the space formed by the cutting away of the skeleton. 100

2. In combination with a double-faced corrugated board having the said facing extended beyond the corrugated skeleton, a stiffening strip of relatively stiffer material located and secured between said facings and abutting against the skeleton. 110

3. In combination with a double-faced

corrugated board having the corrugated skeleton cut away substantially as described, a strip of relatively stiffer material inserted between the opposing facing sheets and occupying the place of the removed portion of the skeleton; said strip being of the same thickness as the corrugated skeleton.

4. In combination with a double faced corrugated board, a strip of the thickness of the

corrugated skeleton and relatively stiffer material abutting the board, and means for securing the said corrugated board, and stiffening strip together. 10

WILLIAM G. CHAPIN.
